(57) **CLAIM**

The ornamental design for a digital video camera, as shown and described.

DESCRIPTION

FIG. 1 is a right side elevational view of a digital video camera showing our new design;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a front and right side perspective view thereof.

The portions of the article in broken lines are shown for illustrative purposes only and form no part of the claimed design.
